UNITED STATES PATENT OFFICE.

RCY W. BROWN, OF AKRON, OHIO, ASSIGNOR TO THE FIRESTONE TIRE AND RUBBER COMPANY, OF AKRON, OHIO, A CORPORATION OF OHIO.

VULCANIZER.

Application filed October 7, 1925. Serial No. 60,951.

This invention relates to vulcanizers of the autoclave press type for tires and the like.

In the vulcanization of tires, it has been proposed to mount the same on expansible cores and enclose them in molds which are placed in a heater and pressed together, usually in a stack, while an expansible curing medium, such as steam or steam and air in admixture, is conducted under pressure into the expansible cores. It has also been proposed to dispense with the cores and to conduct the medium directly into the tires.

The present invention relates to means for effectively draining the supply system for either the cores or the tires, depending upon which of the above procedures are practised, whereby uniformity of cure is obtained.

The conducting of an expansible curing medium into the molds is usually effected through a sectional manifold adapted to be assembled or dismantled as the molds are stacked or unstacked in the heater and, in particular, the present invention relates to an attachment for such manifolds whereby the condensate is automatically removed from the manifold system after each vulcanizing operation is completed so that substantially dry steam will be supplied to the cores or tires at each vulcanizing operation.

The objects of the invention are obtained by the construction illustrated in the accompanying drawings and described below. It is to be understood that the invention is not limited to the specific form thereof shown and described.

Of the accompanying drawings:

Figure 1 is a vertical sectional view partly in elevation, showing a portion of a standard autoclave press for vulcanizing tires and equipped with a device embodying the invention;

Figure 2 is a plan of a portion of the ram showing the device of the invention mounted thereon; and

Figure 3 is a side elevation thereof.

Referring to the drawings, 10 designates the vertical cylindrical heater vessel which is of standard construction and has operable throughout the height thereof, a ram 11 on which the tire molds 12, 12 are stacked with tires indicated at 13 mounted on expansible bags shown at 14 enclosed therein. The stack

of molds 12 is pressed during vulcanization against the usual removable locking cover plate 15.

For supplying steam or steam and air to the bags 14, each has connected thereto a flexible connection 16 extending to a manifold section 17, sections 17 being adapted to be assembled or dismantled as the molds are stacked in or removed from the heater as will be understood by skilled artisans.

According to one mode of practising the present invention, the bottom manifold section is connected onto a drain receptacle 18 mounted on ram 11 and formed of arc shape (Figures 1 and 2) so as to partly encircle the ram about the stack of molds 12.

The supply of steam or mixtures of air under pressure and steam to the manifold may be secured by means of a flexible hose 19 connected onto a nipple 20 extending through the wall of the vulcanizer and connected with an air supply line 21 through a valve 22, a steam supply line 23 through a valve 24, and a blow-off line 25 having a cock 26 therein.

Hose 19 is connected onto a pipe 27 mounted on receptacle 18 and connected by one branch 28 to an inlet 29 in the top of said receptacle, branch 28 having a check valve 28^a therein, and by another branch 30 providing an outlet 31 from adjacent the bottom of receptacle 18, branch 30 having a check valve 30^a therein.

In operation, after the molds are stacked in the heater in the manner shown, steam or steam and air mixtures are supplied thereto by operation of valves 24 or 24 and 22, the steam or steam and air mixture being conducted by hose 19 through branch 28 into receptacle 18 and upwardly through sectional manifold 17 and branches 16 into the interiors of the bags. During this action, the pressure of the steam or steam and air closes check valve 30^a. Steam is also supplied to the heater chamber in the customary way.

During vulcanization, the condensate formed in the manifold system drains down into receptacle 18. Considerable condensate usually forms since the steam supplied the body of the heater is usually at a much lower temperature and pressure than that supplied to the interior of the tires. When the vulcanization has been completed, steam is blown off from the heater, valves 24 and 22

are closed, and cock 26 is opened. This permits the steam to blow off from the bags through receptacle 18. Pressure of the steam will close check 28* and accordingly any water in receptacle 18 will be forced out of the receptacle by the steam past check valve 30* up through hose 19 and out of blow-off pipe 25. The manifold system will thus be freed of water and will be ready for reuse, non-uniform cures due to the presence of water in the internal pressure cure supply system being effectively prevented.

Modifications of the invention may be resorted to without departing from the spirit thereof or the scope of the appended claims.

What is claimed is:

1. Apparatus for curing hollow rubber articles, comprising means for conducting steam into the interior of the article, a vessel adapted to receive condensate from the said means draining therefrom by gravity while the article is curing, and means for blowing off steam from the interior of the article, said vessel being so disposed in the blow-off line that the steam will force the condensate from said receptacle when the steam is blown off after the curing operation.

2. Apparatus for curing hollow rubber articles, including a stack of molds enclosing a plurality of articles, means for conducting steam into the articles, a vessel adapted to receive condensate draining by gravity from the conducting means, and means for blowing off steam from the articles, said vessel being so disposed in the blow-off line that the steam will force the

condensate from the receptacle when the steam is blown off after the curing operation.

3. Apparatus for curing hollow rubber articles, comprising means for conducting steam into or out of the article, a steam supply line connected to said conductor, a blow-off valve in the conductor, and a receptacle arranged in the conductor for collection of condensate draining from the conductor system, said conductor being provided with branches, one having an outlet in the top of the receptacle, the other an inlet at the bottom of the receptacle, a check valve in the first branch adapted to open to the pressure of steam being forced into the article, and a check valve in the second branch adapted to open to the pressure of steam being blown off from the article whereby the drainage will be forced from the receptacle.

4. Apparatus for curing tires in a stack of molds in a heater press, comprising a sectional manifold, branches from the manifold to each tire, a condensate receptacle connected onto the bottom of the manifold, a conductor for supplying steam to the manifold through said receptacle, a branch from the conductor connected to an opening in the top of the receptacle, a second branch from the conductor having an inlet thereinto adjacent the bottom of the receptacle, a check valve opening to the incoming steam in the first branch, and a check valve opening to the blow-off in the second branch.

ROY W. BROWN.
